BIOLOGICAL TESTING DEVICE

Stanley R. Johnson, Fountain Valley, and Arthur P. Stewart, Irvine, Calif., assignors to Baxter Laboratories, Inc., Morton Grove, Ill.

Filed Dec. 21, 1970, Ser. No. 26,609

Term of patent 14 years

Int. Cl. D24—02

U.S. Cl. D16—1

FIG. 1.

FIG. 2.

FIG. 3.

FIG. 4.

FIG. 5.

FIG. 1 is a top perspective view of a biological testing device, with portions of the cover member omitted for ease of illustration; the cover is understood to be uniform at all corners.

FIG. 2 is a top plan view of the device with the cover removed.

FIG. 3 is a sectional view thereof taken on the line 3—3 of FIG. 2.

FIG. 4 is a top plan view of another embodiment of the device.

FIG. 5 is a sectional view of the other embodiment taken on the line 5—5 of FIG. 4.

We claim:

The ornamental design for a biological testing device, as shown and described.
